INVENTOR

Victor J. Evans

ATTORNEY

WITNESS:

E. R. Ruppert.

UNITED STATES PATENT OFFICE.

NELSON J. AUGER, OF NEWBURYPORT, MASSACHUSETTS.

SHADE BRACKET.

Application filed April 30, 1925. Serial No. 27,039.

This invention relates to improvements in expandable and adjustable shade bracket supports and contemplates the provision of a pair of flat strips, one sliding within the other, and each including a plurality of spaced sockets arranged thereon and adapted to receive the usual and conventional form of shade bracket supports therein.

Another object of the invention is the provision of locking means arranged centrally of the length of the two sliding bars and adapted for rotation upon one of the bars and having rods extending from the opposite ends thereof and connected to the bars in order that rotations of the member will in turn move the rods inwardly and outwardly with respect and hold the same in rigid locked positions.

With the above and other objects in view, the invention further includes the following novel features and details of construction, to be hereinafter more fully described, illustrated in the accompanying drawing and pointed out in the appended claims.

25 In the drawing:—

Figure 1 is a front elevation of my invention shown applied to the upper portion of a window frame.

Figure 2 is a similar view of my invention showing the manner in which the rods may be expanded.

Figure 3 is a top plan view of the same and showing the manner in which a shade roller is supported thereon.

35 Figure 4 is a vertical sectional view taken on line 4—4 of Figure 2.

Figure 5 is a fragmentary perspective of one of the rods and showing the manner in which a shade bracket is supported thereon.

40 Figure 6 is a fragmentary top plan view of the locking means.

Figure 7 is a perspective of a detachable knob for the locking means.

Referring to the drawing in detail, wherein like characters of reference denote corresponding parts, the reference character 10 indicates the upper portion of a window frame and to which the present invention is applied.

50 The invention residing in the provision of a pair of relatively flat bars 11 and 12 respectively, the bar 11 having its edges bent inwardly and downwardly and in spaced relation with respect to the inner side thereof while the bar 12 has its edges bent over and lying flush with the rear side upon its inner

end. These bars 11 and 12 are adapted to slide one upon the other; the bar 12 is adapted for sliding movement upon the rear side of the bar 11 and between the bent edges thereof. The outer ends of these bars 11 and 12 are bent inwardly and include penetrating points thereon which are adapted to engage the outer sides of the window frame 10 in order to support the device thereon and in order to prevent further accidental displacement of my invention I provide a pair of supports 14 which extend from the rear sides of the bars 11 and 12 and including upwardly extending end portions 14' which are received within the bent edges of the bars while their upper ends are inwardly offset and include penetrating points thereon which engage the upper sides of the window frame 10. The expandable means is in the form of a disk 15 having strips 16 provided at diametrically opposite sides thereof and extending over the inwardly bent edges of the bar 11 and adapted for sliding movement thereon. A cross key 17 is pivotally mounted upon a stud bolt 18 or the like which extends outwardly from the face of the disk 15 and which has secured adjacent the opposite ends thereof a pair of rods 19 which in turn have their ends looped within any one of a plurality of openings 20 provided in the strips 11 and 12. I also provide further locking means for the strips 11 and 12 in the form of ears 20' upon opposite sides of the intermediate portions of the key 17 and extending in oppositely disposed relations thereon and including lugs 21' upon their under sides which are adapted to be brought into selective engagement with openings 21' provided in the disk 15.

In order to provide means adjacent the ends of the bars 11 and 12 for supporting the shade brackets, as mentioned in the foregoing, I provide a plurality of sockets in the form of cross section substantially V-shaped flanges 21 which are secured in spaced relation and at an inclination upon the outer sides of the bars 11 and 12. These flanges are adapted to receive the correspondingly shaped portions 22 which are provided upon the ends of shade brackets 23.

In order to provide means for supporting curtains, draperies and the like I provide elongated pole or rod supporting brackets 23' having correspondingly shaped inner end portions which are received within the

outer pair of sockets provided upon the outer ends of the bars 11 and 12; while a rod 24' may have its ends secured to the correspondingly outer ends of the pole or rod 5 supporting brackets 23'.

In the mode of operation of the present invention it is clearly apparent that upon turning the cross key 17 in a clockwise or counter-clockwise movement upon the outer 10 face of the disk 15 and upon the stud bolt 18 through the instrumentality of a knob 17' having an elongated plate 18' secured to its lower end while prongs 19' extend downwardly from the opposite corners thereof 15 and receive the outer edges of the key 17 therein that the rods 19 will pull or throw the bars 11 and 12 inwardly and outwardly.

It is also to be noted that owing to the relative positions of these cross section substantially V-shaped flanges 21 arranged at spaced intervals and at inclinations with respect to the bars 11 and 12 that the ends 22 of the shade brackets 23 may be readily and easily inserted therein for supporting the shade roller 24. Owing to the simple construction and novel arrangement of parts forming this invention it is noted that a very useful and advantageous shade bracket is provided which may be readily and easily attached to a window frame without marring or defacing the same in any way whatsoever.

The invention is susceptible of various changes in its form, proportions and minor 35 details of construction, and the right is herein reserved to make such changes as properly fall within the scope of the appended 75 claims.

Having described my invention what is 40 claimed is:

1. A shade bracket of the character described comprising a pair of bars adapted for sliding movement one upon the other and having their respective ends bent inwardly with securing means thereon, a disk 45 having a pair of strips extending at diametrically opposite sides thereof and bent over and upon one of the bars, a cross key pivotally mounted upon the outer side of the disk, a pair of rods having their inner 50 ends secured adjacent the outer ends of the cross key and their opposite and outer ends secured to the bars, and shade roller supports having their end portions arranged upon the outer ends of the slidable bars. 55

2. A shade bracket of the character described comprising a pair of bars adapted for sliding movement one upon the other and having their respective ends bent inwardly with securing means thereon, an 60 apertured disk having a pair of strips extending at diametrically opposite sides thereof and bent over and upon one of the bars, a cross key pivotally mounted upon the outer side of the disk, ears carried upon 65 the opposite sides of the intermediate portions of the cross key and including lugs upon their under sides adapted to be brought into selective engagement with the apertured disk, a knob having a plate secured to 70 its inner end which includes downwardly extending prongs upon its corner to receive the cross key therein, a pair of rods having their inner ends secured adjacent the outer ends of the cross key and their opposite and outer ends secured to the bars, and shade roller supports having their end portions arranged upon the slidable bars. 75

In testimony whereof I affix my signature.
NELSON J. AUGER.
